UNITED STATES PATENT OFFICE

OTTO ULRICH, OF CRONBERG-ON-THE-TAUNUS, GERMANY

ADVERTISING DEVICE

Application filed August 11, 1931, Serial No. 556,362, and in Germany August 14, 1930.

The present invention relates to an advertising device which may be adopted in all kinds of table accessories, such as ash-trays, match-stands, wine lists and menu cards and the like as publicly displayed in hotels.

This device is first and foremost intended to appeal to the playful instinct of everyone inasmuch as the apparatus is to be operated by the person handling it.

10 The effect of advertising matters as known heretofore are more or less uninteresting since they do not arouse the curiosity of the observer. This also applies to mechanically actuated or illuminated advertising matters 15 as used for example by business houses.

This inefficiency is entirely removed by the present invention due to the fact that the interested person himself, by actuating a driving mechanism is able to set an advertising strip in motion. The band provided with the advertisements contains mainly entertaining and amusing matters of interest to the public, such as for example, anecdotes, news cartoons, fashion news, travelling information, plan of theatres, varieties and cinemas and the like intermixed with advertisements. By pressing down the operating lever once, various pictures are caused to appear behind the windows on all sides of the 20 apparatus and will be seen by the visitors. The invention in general, thus relates to picture bands, as referred to above, actuated by a special driving mechanism and caused to proceed in such a manner that various pictures are continuously shown simultaneously 25 in all the windows.

The picture strips used according to the invention are alternately unwound from one reel and wound on another.

40 These reels are so operated over a change gear wheel that the picture band moves over special guide rollers behind the windows of the device. When the strip has run to the end in one direction, the end of the band effects a release in the empty reel, said release causing the drive to be changed in such a manner that the band is caused to travel in the opposite direction when the same lever movement is executed.

50 The nature of the invention is embodied

in this action, namely, that the film band is caused to travel first in the one direction and then in the other by actuating the driving lever as desired, a mechanism being released as soon as one of the reels is empty, which in 55 turn causes a snap catch to operate and the gear wheel mechanism driving the reels to be switched over, causing the band to travel in the opposite direction.

A spindle with steep threads on which a 60 nut may be moved up and down by means of a cog wheel coupling over a toothed wheel constitutes the drive for the reels.

An embodiment of the invention is shown in the accompanying drawings. 65

Figs. 1 and 2 show respectively a side and plan view of the device,

Figs. 3 and 4 are views of the device with the casing removed, Fig. 3 showing the guide rollers and Fig. 4 the bearings for the 70 driving lever separately.

Figs. 5 and 6 are views in horizontal section, Fig. 5 showing the relative positions of the guide rollers and the band guide together with the lever arrangement and Fig. 6 the 75 relative positions of the driving wheels.

Fig. 7 shows the driving spindle together with its coupling.

Figs. 8-14 show a view, plan and section of the film spools in two positions together 80 with the change-over device, i. e. the position it takes up when engaging and disengaging the driving wheel when the film band is wound and unwound. Figs. 13 and 14 respectively represent sections on the line 85 A-B of Figs. 8 and 11, whereas Fig. 9 is a plan and Figs. 10 and 12 views from below.

Fig. 15 shows an enlarged view of the lever switch for the alternating drive of the film spools, and 90

Fig. 16 the device in reverse position to that shown in Fig. 15.

The advertising device comprises a casing 1 provided with a window *a* on each side. 95 The bottom of the casing may be of any desired shape. A top plate 2 carries an ash-tray 3 together with a match box holder 4. The bottom portion 5 is closed by a plate 6 so that a false bottom is formed in which the toothed wheels of the switch drive are fixed. 100

The lever 7 projects out of a slot in the casing 1 and moves downwardly into the position indicated by dotted lines when the knob 8 thereof is pressed down.

5 Within the casing 1 and on the false bottom 5 a double wall 9 is fitted forming a cylindrical space in which the driving spindle 11 is mounted. The two wall portions, 9, 9 form the bearing for the lever 7, which is 10 loosely suspended at 12 by means of a pin 15 to the two levers 13 and 14. The walls 9, 9 are provided with an opening 16 so as to make the lever more accessible during assembly. The lever, at 17, carries a counter 15 weight so as to ensure that its knob 8 is always raised again after having been depressed or that the forked end 19 which carries the coupling 18 is brought to its lowest position and thus prepared for further 20 operations. The coupling 18 constitutes a hollow cylinder through which the spindle 11 is passed. The nut 20, the teeth 21 of which engage the teeth 22 of the coupling 18, runs on the spindle. The forked end 19 of the lever 7 is shown enlarged in Fig. 7, in which it is plainly seen how the coupling 18 pivots on the pin 23 but yet is mounted so as to be non-rotatable in relation to the spindle 11. The weight of the nut 20 causes it to 25 rest against the teeth of the coupling 18. When the lever 7 is moved by pressing the knob 8, its forked end 19 is lifted upwardly. The nut 20 cannot rotate due to the fact that it engages the teeth of the coupling 18 with 30 the result that the spindle 11 is forced to rotate carrying with it in its rotation the toothed wheel 24, mounted on its lower end. The knob 8 is now released whereupon the weight 35 17 causes the fork 19 together with the coupling 18 to fall. The nut is then disengaged from the teeth 22 and drops on the spindle thread of the coupling. The friction between the spindle and the nut causes said nut to travel down the spindle slower than the dropping coupling 18 with the result that 40 only upon the coupling reaching its bottom position can the nut again engage its teeth so that both members are prepared to carry 45 out the operation afresh, i. e. to drive the spindle and consequently also the toothed wheel 24 as soon as the lever 7 is depressed. The point 25 of the spindle 11 is pivoted at 26a in a corresponding recess in the arm 26 (Fig. 3—the fixing of this arm 26 will be 50 fully explained in a later paragraph) and its point 27 in a bearing 28 arranged in the cover plate 29 which partitions off the space 10 and is riveted in position. This plate, at the same time, by means of its two free ends 55 30 and 31, serves as a spring bearing for the guide rollers 32 and 33. In the same manner a covering plate 34 is fixed to the walls 9, furnishing a spring bearing for the guide 60 rollers 37 and 38 (Figs. 5 and 3) by means of its two free ends 35 and 36. The points of

the rollers 32, 33, 37 and 38 are readily fitted to rotate in corresponding bearings in the false bottom 5. The bearings for the spools 39 and 40 will be described later.

The film band 41, for example, runs from 70 the spool 39 over the rollers 37, 32, 33, 38 to the spool 40 (Figs. 5 and 6) or reverse if the driving mechanism is actuated.

Fig. 6—the lever arrangement having been omitted—shows the manner in which the 75 toothed wheel 24 of the spindle 11 is positioned in relation to the toothed wheel 42 so that the spool 39, mounted over this wheel, rotates with it. In this position the lever 26 which provides the bearing point 25 for 80 the spindle 11 and which is pivoted at 43 has dropped down in the plane of the drawing. If the lever 26 is raised the toothed wheel 24 85 engages the other toothed wheel 44, thus rotating the spool 40 disposed over said wheel and causing the film band to run in the opposite direction.

In Figs. 15 and 16 may be seen enlarged views of the drive which facilitates the alternate movements on the part of the lever 26. 90 It comprises a flat bar 53, slidably arranged between the two pins 45 and 46 on the plate 6. This bar is suspended by means of the lug 47 and the spring 48 to a pin 49 fitted in the plate 6. Due to it being slidably arranged, its longitudinal slot 50 fits over the pin 49. The lever arm 52, pivoted at 51 to the bar 53, and urged by the spring 48, causes said bar 53 to press the edge 54 of the lever arm 52 continually against the point of the lever 26 which 100 alternately strikes against either the pin 45 or pin 46 according to the position of the lever 52 in the manner indicated in Figs. 15 and 16. Additional stops 55 and 56 determine the two 105 extreme positions of the lever 52 in relation to the bar 53 which, on changing over, always presses against the lever under the action of the spring 48. This slideable spring type bearing of the snap drive is necessary when the lever 26 is thrown from one position over 110 to another. This movement takes place in the following manner:

The shafts 59 and 60 are mounted on the base plate 6 in the projections 57 and 58. The toothed wheels 42 and 44 together with 115 their sleeves 61 and 62 are mounted on these shafts, said sleeves serving as bearings for the spools 39 and 40. The sleeves and spools rotate loosely in opposite directions and are interconnected by means of a bolt or pin 63 120 slidably mounted in the spool. (This action will be described later.) The end of the film band, fastened to the empty spool, moves the interconnected spool a further three quarter revolution and on this rotation of the pin 63 125 which is of such a length that it projects under the toothed wheel, comes to rest against the arm 64 of the lever 52 and thus turns the lever on its pivot 51 (Fig. 15). During this movement the lever, together with the bar 53 130

- which presses with its edge 54 against the point of lever 26, is pressed down by this lever 26 and forces the lever 52 into the position shown in Fig. 16 with the aid of the spring 48, causing the lever 26, carried on its pivot, also to drop into this position i. e. according to Fig. 16. The bearing 26a, with the spindle 11 and the toothed wheel 24, is thus switched over, with the result that this now engages the toothed wheel 42 opposite to the previous position and according to Fig. 15. The spool 39 is now brought into action and winds the film thereon, whereupon the band which is placed around the circumference of the spool automatically withdraws the pin 63 from the toothed wheel 42 and thus when the other spool is empty, causes the coupling for the change-over to perform its operation there. When the spool 40 is empty, its bolt 63 will be placed against the shoe 65 by means of a cam 66 of the lever 52 (Fig. 16), with the result that the lever 52, according to the plane of the drawing, (all the levers are fitted horizontally in relation to the plate 6 in the device) must swing upwardly when the same operation for the change-over into the position according to Fig. 15 is carried out as described in conjunction with the previous changing-over operation.
- 30 The description given above shows that, by actuating the lever arrangement according to the invention, a spindle movement is obtained which forces the other drives to cooperate automatically with each other and cause an alternative operation in such a manner that the film band is displayed to the user of the apparatus in the one direction as well as in the other as compared to previous devices in which the band runs continuously in one direction only, whereas the other direction serves to restore the band to its original spool.
- Finally the engaging and disengaging movement of the spools with their associated toothed wheels according to the invention is shown. This action will be explained in conjunction with the spool 39 according to Figs. 8-14.
- 50 The spool is provided with an open portion 67 through which projects a vane 68 fastened to the bolt 63. The bolt is set under the pressure and rotating action of the spring 69, disposed in a groove so that the vane 68 is adapted to swing out of the opening and in toward the spool. The bolt 63 is mounted in a sleeve 70, firmly fixed in the spool. Under the action of the spring 69 the vane slides on the cam 71 of said sleeve 70. It may be seen from the drawing that, 60 when the vane has swung inwards, it is set in its top position and the bolt is withdrawn and does not project over the lower surface of the toothed wheel 42. The spool and the toothed wheel are thus coupled in the manner shown in Figs. 8 and 10 but the pin 63 is unable to encounter the corresponding arm of the lever 52. The Figs. 11 and 12 indicate in which manner the vane 68 swings out of the opening 67 and the pin 63 projects downwardly. The reels are of such a height that they fit into the lighted portion of the casing 1. In order to cause the film band to be wound and unwound under a definite tension, the reels are in the upper ends provided with a braking device 73 of known type which slides on the inside of the cover plate of the casing 1.
- According to the height of the reels, rods 74 of corresponding length are inserted in the ends of the film band so as to facilitate the fixing of the band 41 into the groove 75 (Fig. 9). The film issues through the slot 76 as will be seen in Figs. 13 and 14. Fig. 13 shows the manner in which the wound band presses the vane 68 into the opening 67 against the action of the spring as indicated by the arrow 77. How the vane is adapted to swing out freely when the spool is empty is clearly seen in Fig. 14. In this position the pin 63 is depressed so as to cause the change-over as illustrated in Fig. 11.
- What I claim is:
1. An advertising device comprising, in an inclosing case, having windows in its side walls, two reels, a gear wheel coupled to each of said reels, a picture band wound upon one of said reels, guide rollers arranged to guide said picture band along said windows to the other of said reels, a counterweighted lever having a forked end, a coupling pivotal-
ly mounted on this end, and adapted to en-
gage with a nut movable on a vertically ar-
ranged threaded spindle, a pinion mounted
on said spindle and engaging with a gear
wheel coupled to one of said reels and a switch
gear adapted to automatically disengage said
pinion from said gear wheel and engage it
with the gear wheel coupled to the other of
said reels when the picture band has been
wound on said first reel and unwound from
said other reel, substantially as set forth.
  2. A switch gear comprising, in combina-
tion, a base plate, a two-armed lever pivot-
ed on said base plate, a pinion journaled in
one arm of said lever, the other arm of said
lever being pointed at its end, a flat bar slid-
ably arranged on said base plate, a second
lever pivoted on said bar, a sliding edge on
said second lever, a spring arranged to urge
said edge against the point of said first le-
ver, two gear wheels arranged to be alter-
nately engaged by said pinion, the arms of
said second lever extending under said gear
wheels, and means to couple the gear wheel
engaging with the pinion to the correspond-
ing arm of said second lever to switch both
said levers over and engage the pinion with
the other gear wheel, substantially as set
forth.
  3. An advertising device comprising in

combination an inclosing case having windows in its side walls, two reels having gear wheels coupled to them, a picture band secured to both said reels, guide rollers arranged to guide said picture band along said windows, a lever operated spindle having a pinion mounted on it and journaled in one arm of a lever, the other arm of said lever having a point resting against a sliding edge 10 provided on a second lever pivoted on a slideable bar, a spring acting to urge said edge against the point of said first lever, arms on said second lever extending under the gear wheels coupled to said reels, in each reel an 15 opening, a sleeve inserted in each reel having a cam provided on its upper end, a bolt in said sleeve, a vane secured to said bolt and resting on said cam, a spring acting to turn said vane out of said opening and press said bolt down to encounter the corresponding arm of said second lever, substantially as set forth.

20

In testimony that I claim the foregoing as my invention I have signed my name.

25 OTTO ULRICH.
